Daniel E. Paris, of Troy, New York.
Letters Patent No. 1878-Dated Dec. 15th 1868.
Design for a Stove Plate.

The schedule referred to in these Letters Patent and making part of the same.

To all whom it may concern:

Be it known that I, Daniel E. Paris, of the City of Troy, in the County of Rensselaer and State of New York, have invented or produced a new and original ornamental Design for Stove Plates; and I do hereby declare that the following is a full and exact description of the same, reference being had to the annexed photographic drawing of a portion of a stove plate bearing my said ornamental design.

This ornamental design for stove plates consists of a peculiarly shaped double-ended, reverse-curving, vine 9.9.9.9. having curling leaves 2.2.2. in the bays of its curves, and arranged in an oblong rectangular panel I.I, all as shown by the annexed photographic drawing.

What I claim as new and of my invention or production and desire to secure by Letters Patent is the ornamental design for a stove plate as shown and described:
